Matthew Hodkinson

UNITED STATES PATENT OFFICE.

MATTHEW HODKINSON, OF PITTSBURG, PENNSYLVANIA, ASSIGNOR TO M. HODKINSON, JR., OF SAME PLACE.

IMPROVEMENT IN RETORTS FOR DISTILLING COAL-OIL.

Specification forming part of Letters Patent No. 26,326, dated November 29, 1879.

To all whom it may concern:

Be it known that I, MATTHEW HODKINSON, of the city of Pittsburg, county of Allegheny, and State of Pennsylvania, have invented a new and useful Improvement in the Construction of Retorts for the Manufacture of Coal-Oil, &c.; and I do hereby declare that the following is a full, clear, and exact description of the construction and operation of the same, reference being had to the accompanying drawings, in which—

Figure 1 is an end view of the retort, and Fig. 2 is a horizontal projection of the interior, arrangement and gearing of the said machine.

The nature of my invention consists in placing a revolving shaft longitudinally through a metallic or other cylinder, the said shaft being armed with semicircular knife-edges, and always revolving in the direction of the knife-edge, the edge being in advance. The knives are movable at the will of the operator, being fastened in by keys or other mechanical arrangement.

In order to enable others skilled in the art to make and use my invention, I will proceed to describe its construction and operation.

A metallic or other cylinder of convenient dimensions—say eight feet long by four feet diameter—is constructed and placed permanently in its bed over a furnace, the upper part or top of the cylinder being so made as to open or to be removed for the purpose of receiving the coal from which the oil is to be extracted. A revolving shaft, A, Fig. 2, passes longitudinally through the center of the cylinder, one end of which, a, Fig. 2, rests against one of the cylinder-heads, while the opposite end, A', Fig. 2, passes through the other head and projects beyond it, and is terminated by and armed with a cog-wheel, c, Fig. 2. A shaft, D, Fig. 2, properly supported and driven, is armed with cog-wheels d, Fig. 2, which mesh into the cogs of the wheel c of the cylinder-shaft and impart mo-

tion to it. The cylinder-shaft A has fastened to it, by key or otherwise, certain knives, B, Figs. 1 and 2, formed like the tooth of the cultivator. On the end of the cylinder opposite that at which the power is applied is a man-head, E, Fig. 1, near the bottom, so as to charge and draw. The gas is permitted to escape through an aperture in the upper end of the cylinder and over the man-head, and this is an improvement on the revolving cylinder or retort, because the oil is less impregnated with dust or small particles of coke, and the aperture is less liable to be filled or choked up with the same.

The operation of the machine is as follows, the sections of two retorts being shown in Fig. 2: The retort being charged with coal, power is applied to the shaft D, and communicated to the shaft A, which revolves, and the knives break up the coal, and by the application of heat the oil is given out freely and the gas evolved. By this arrangement and operation the coal is removed from the surface toward the center of the retort, thus subjecting it more equally to the heat of the furnace, and by so doing the gas is readily and thoroughly evolved, yielding all the oily matter in a shorter time and by a less degree of heat, giving the oil a better color and smell, scorching it less, and saving a large amount of fuel.

I do not claim the use of a shaft armed with agitators within a retort; but

What I do claim as my invention, and desire to secure by Letters Patent, is—

The stationary retort with a shaft armed with knives whose edges are at right angles with the shaft passing through it, by which, when motion is given to the shaft, the coal is broken and pulverized more effectually and more economically than by any other method.

MATTHEW HODKINSON.

In presence of—

NICHOLAS K. WADE,
ORLANDO METCALF.
